UNITED STATES PATENT OFFICE.

WILLIAM A. EUDALY, OF CINCINNATI, OHIO.

DOWNDRAFT BRICK-KILN.

SPECIFICATION forming part of Letters Patent No. 508,003, dated November 7, 1893.

Application filed May 28, 1892. Serial No. 434,783. (No model.)

To all whom it may concern:

Be it known that I, WILLIAM A. EUDALY, a citizen of the United States, residing at Cincinnati, in the county of Hamilton and State 5 of Ohio, have invented certain new and useful Improvements in Brick-Kilns for Burning All Kinds of Clay Wares; and I do hereby declare the following to be a full, clear, and exact description of the invention, such as will enable 10 others skilled in the art to which it appertains to make and use the same.

My invention relates to certain improvements in kilns for burning brick, tile, pottery and other ceramic products.

15 The object of my invention is to provide an improved kiln having in view a more equal distribution of heat, giving more uniformity in burning, a more perfect combustion, producing greater economy of fuel and labor.

20 My invention consists in, providing an improved kiln with furnaces or heat producers each having a double crown with an air chamber between the upper and lower crowns, which air chamber is adapted to convey the 25 external air to the products of combustion in the combustion chamber situated within the kiln proper by means of air flues entirely exterior to the furnace or furnace throat as hereinafter set forth.

30 My invention consists further in providing a kiln with double bag walls situated within the kiln having air chambers between these two walls each connected with the external air by means of air flues situated at the bottom of said chamber as and for the purposes 35 hereinafter more fully set forth.

My invention consists further in providing 40 a kiln and the furnaces of the same with a system of hot air flues and chambers located in such positions that the external air passing into the furnace and combustion chamber is made to modify and equalize the heat in the brick work forming these parts of the furnaces, bags or combustion chambers and 45 kiln walls as hereinafter described, in this way greatly increasing the durability of the kiln.

My invention consists further in certain 50 other details of construction which will hereinafter be more fully described and set forth in the claims.

Referring to the accompanying drawings:— Figure 1 represents a horizontal sectional view of my improved kiln built with round bag walls, taken on line 1—1 of Figs. 3 and 4. Fig. 2 is a horizontal sectional view of the same, built with straight bag walls, taken on line 1—1 of 55 Figs. 3 and 4. Fig. 3 is a transverse vertical section on line 3—3 Fig. 1. Fig. 4 is a transverse vertical section on line 4—4 Fig. 1. Fig. 5 represents a perspective view of the furnace broken so as to show the connection of the furnace, main walls of kiln, bags, air chambers and air flues. Fig. 6 is a horizontal sectional view of my improved kiln, built round, with round 60 bag walls, taken on line 1—1 Figs. 3 and 4. Fig. 7 is a longitudinal vertical section on line 7—7 Fig. 1. Fig. 8 is a transverse vertical section of the furnace on line 8—8 Fig. 1. Fig. 9 is a longitudinal vertical section on line 9—9 70 Fig. 1. Fig. 10 is a longitudinal section of the furnace cutting the kiln and bag walls on line 10—10 Fig. 1.

In the drawings W represents the outer wall of the kiln which may be constructed of 75 any desired form or size, either square, oblong or round to suit the capacity and convenience of the plant.

The bottom of the kiln is divided into compartments H, H and T wholly beneath the 80 floor of the kiln by the solid division walls S S. Each of the compartments H is provided with a large transverse exit flue F leading to a separate chimney C adapted to be regulated by a damper d from the outside of 85 the kiln. The chimneys C C are preferably located within the main wall W of the kiln, though they may be built wholly or partially within or without the wall W.

Each section T or center portion of the kiln 90 is provided with a large exit flue V, which in oblong kilns is divided in the center and connected with a chimney C at each end of the kiln.

In round kilns or very long square kilns 95 that portion of flue V which passes through one side compartment H, in order to connect with a chimney C in the main wall W is enclosed so as to exclude all the heat from section H or other part of the kiln except that 100 entering flue V from the middle or center section T of the kiln. By this arrangement all

the heat can be drawn to the center of the kiln, or by closing the damper in the chimney leading from flue V the heat can be thrown to the outer rim of wall of the kiln, thus by 5 the shifting of the heat greater uniformity can be attained. Each section H and T is again laterally subdivided by a number of small division walls s s between which is a series of small flues p, p, leading to the large 10 flues F V. Each compartment H T together with the small and large flues leading from the same is connected with a perforated floor of brick work L, which when completed constitutes the bottom or floor of the kiln on 15 which the wares are set for burning. At the ends of the flues F V are openings A through which air is admitted in cooling the kiln.

B, represents the bags or combustion chambers which may take a variety of forms and 20 illustrated by a semi-circle in Fig. 1 or straight, as in Fig. 2.

In my invention the bags B are made to 25 serve the double purpose of conducting the heat from the furnaces G to the top of the kiln where it is distributed to the wares to be burned, and that of a combustion chamber, which taken in connection with the furnace proper cause the escaping products of combustion on their passage from the furnace 30 to the kiln to converge at a point above the top of throat M, at which convergent point they become thoroughly mixed with cross currents of hot air escaping into the bag from the air chambers O and D, through 35 openings t and q.

The bag B is inclosed on the outer sides or next the furnace by the kiln wall W, and on the inner side or next the wares to be burned by a suitable double wall h, i; h, being the 40 outer portion or bag wall proper and i, being the inner portion or bag lining. The bag lining i may extend only partially up or to the full height of the bag, depending upon the form of the bag and kind of wares to be 45 burned.

O, is an air chamber situated between the bag wall h, and the bag lining i, and is preferably connected with the external air at the bottom of the ash-pit by one or more air flues 50 f f, which pass into the bag foundation K, and turning upward enter the air chamber O, at the bottom of the bag wall as seen in Fig. 5. This chamber O should be closed at the top by uniting wall h and lining i so as to force 55 the air from chamber O through openings t t into the combustion chamber B below the top of the wall h, i. In this way the air escaping from chamber O in connection with the air from air flue a through opening q becomes 60 thoroughly mixed with the products of combustion in bag B. before passing out of bag B. into the kiln proper.

The objects of the air chamber O, and air flues f and t, are, first, to supply air heated to 65 a sufficient temperature to insure the perfect combustion of the gases that may escape

from the furnace G as they pass through the bag or combustion chamber B and, by this arrangement the products of combustion are thoroughly consumed before entering the 70 burning chamber of the kiln proper, thus preventing the fire-marking of the wares, which would be the result if the products of combustion were allowed to enter the burning chamber unconsumed. It has been found 75 that different gases passing through the same flue at the same time in the same direction do not readily mix or commingle; hence in my invention the air supply currents from air chambers O and D are made to strike the escaping unconsumed gases and particles of fixed carbon in cross section while within the combustion chamber B, which affords a more thorough mixing of fresh particles of air with the volatile fuel and hence better combustion; second, it has heretofore been almost impossible to prevent the too rapid heating and overburning of the wares placed next the bag walls.

In my invention, chamber O, flues f and t 90 afford a constant current of air passing between the inner wall i, and the outer wall h, by which the temperature on the inside of the kiln next the bag walls h, is equalized, thereby preventing the too rapid heating or over-burn- 95 ing of the wares in this portion of the kiln.

N, represents air chambers in each of the side walls of the furnace G and are connected with the external air by air flues n n. Openings e e, and k k, connecting air chambers N N, and air flues m m respectively with the furnace G supply heated air to the gases above the fuel on the grate bars g.

D, indicates an air chamber outside the kiln wall W between the upper and lower 105 crowns of the furnace G, and is connected with the external air by air flues c c; and with the bag or combustion chamber B by air flues c a, at the points q q which openings q q should begin just above the arch over the 110 throat of the furnace, the object being to admit the air as low down in the bag B as possible, to insure a more thorough mixing of the air and gases before they escape from the combustion chamber. 115

By means of the double crown, the inclosed air chamber D and the connecting flues c c and a a, the heat that would otherwise be lost at the top of the furnace by radiation is caused to heat currents of air in their passage through flues c c, a a and chamber D. These currents of hot air escaping from chamber D through flues a a, are distributed to the gases in the combustion chamber B at several points q q, in the lower portion of bag 120 B, thus insuring a more perfect combustion of the same.

The air chambers D, N and air flues m m at the top and sides of the furnace, the air flues f f and chamber O in the bag walls and 130 the air flues a a, in the main wall of the kiln serve the additional purpose of cooling the

fire brick lining of the kiln, bag walls, and kiln wall inside of the bags; in this way giving greater durability to the kiln.

5 *r* represents an opening through the bag wall at or near the bottom, passing through but not connected with air chamber O and adapted to be closed by a damper (not shown) by which any desired portion of the heat from the furnace can be distributed directly 10 to the wares at the bottom or floor of the kiln, and in passing through the bag walls *h* and *i* aids in heating the air in air chamber O.

15 *g* represents the grate bars which may be any one of a variety of forms and when desired set so that the outer end may be a great deal higher than the inner end; thus forming a slanting grate.

20 *M* is the furnace throat, or that part of the furnace within the main wall of the kiln and is formed by turning an arch in the main wall of the kiln so as to extend below that portion of the furnace crown exterior to the kiln wall *W*. This in connection with the 25 slanting grate forms a gas reservoir *M'* beneath the crown of that part of the furnace exterior to the main wall of the kiln. In this way a bridge wall also is formed at the 30 top of the furnace, which in connection with the bridge wall at the bottom contracts the rear end of the furnace so as to produce a more thorough mixing of the hot air supply with the volatile matter of the fuel, and at the same time cause these mixed gases to descend from the gas reservoir *M'* beneath the 35 outer end of the crown, and be impinged upon the incandescent fuel at the rear end of the grate bars as they pass through throat *M* to bags *B*, thus insuring more perfect combustion.

40 The operation of my improved kiln is as follows:—The brick or other wares to be burned having been properly set in the kiln the fires are started in the furnaces and kept at a very low temperature until the wares are thoroughly water smoked or dried. The fires are 45 then increased gradually to the finish. As the heat increases in the kiln the burner or man operating the kiln examines the condition and temperature of the wares through 50 the peep or test holes *P P*. If, at any time any compartment or section of the kiln is found to be heating too rapidly the dampers *d*, in the chimney of that compartment are partially or entirely closed as the condition 55 of that particular section may require and the heat is driven to the adjoining compartments not so hot. Heretofore great difficulty has been experienced in burning the wares in the center of wide kilns. Especially is this 60 the case in round kilns of large diameter. In my invention the center compartment or section *T* enables the operator, by closing the damper in the chimneys leading from the sides or outer compartments, to drive any desired portion of the heat to the center of the kiln that it may escape through the flue *V* and chimney leading from compartment *T*.

Or, should the center or middle of the kiln become too hot the damper in the chimney leading from the center can be closed causing the heat to seek an outlet at the sides or outer portion of the kiln. In this way the burner has complete control of the kiln and by a little care in handling the dampers greater uniformity in burning can be had 70 than has heretofore been attained. The furnaces and combustion chambers are adapted to the use of any kind of fuel. After the fires have been lighted and the furnaces brought to a moderate degree of heat the volatile matter or gases are liberated from the fuel, and being much lighter than the fixed carbon rise 75 to the top of the furnace or gas reservoir *M'* beneath the outer end of the furnace crown at which point they become mixed with the air entering through the openings *e e* at the 80 sides of the furnace. These mixed currents passing back strike the bridge wall at the top of the furnace and are drawn downward through throat *M* toward the incandescent fuel on the rear end of the bars; at this point the gases meet and are mixed with the cross-currents of hot air entering through the openings *k k* leading from flues *m m* at each side of the furnace. By this arrangement the 85 gases are supplied with the necessary oxygen and by coming in contact with the incandescent fuel at the rear of the bars are heated to that temperature required to produce perfect combustion. It has been found, however, 90 that in practice, it is impossible, with a strong draft in the kiln, to prevent a portion of the gases and small particles of fixed carbon from passing into the bag or combustion chamber *B* unconsumed. These unburned gases having 95 reached the bag *B* will pass through said bags unconsumed and mingle with the wares in the kiln, unless supplied with the requisite amount of air heated to a proper temperature 100 to insure perfect combustion before escaping from the top of the bag. In my invention this is accomplished by aid of air chambers O and D, and the connecting air flues which supply 105 hot air through openings *t t*, and *q q*, in cross section, which insures a more perfect mixing 110 of the air and gases and hence a more perfect combustion of these gases and particles of fixed carbon, while within the bag or combustion chamber, in other kilns, especially with strong draft, these particles of combustion are drawn through the bags unconsumed 115 and are not only lost to the heat producing force of the fuel but causes great damage by passing through and discoloring the wares in the kiln. All the inlet air flues are adapted 120 to be controlled by dampers on the outside of the kiln or furnaces so that any desired quantity of fresh air can be supplied to the furnace and combustion chamber depending 125 upon the kind of fuel being used.

130 It is evident that various changes might be made in the form, constructions and arrangements of the parts described without departing from the spirit and scope of my invention.

tion. Hence I do not wish to limit myself to the construction herein set forth.

Having thus fully described my invention, what I claim, and desire to secure by Letters 5 Patent, is—

1. A down-draft kiln having its bags or combustion chambers situated wholly within the kiln, the inner side of said chamber being formed by double walls, said walls inclosing an air chamber, said air chamber being closed at the top and connected at the bottom with the external air by means of air flues and with the lower or middle portion of the combustion chamber by means of openings through the inner side of the double wall substantially as described.

2. In a down draft kiln, hollow bag walls, in combination with furnaces having double crowns adapted to admit heated air to both sides of the combustion chamber in cross sections as and for the purposes set forth.

3. A down draft kiln having air inlet flues leading into the upright combustion chamber from opposite sides of the same and transverse to the length thereof.

4. A down draft kiln having furnaces with double crowns, vertical air flues in the main wall of the kiln connecting the air chamber in the double crown with the combustion chamber at various points.

5. A kiln having its upright combustion chamber provided with air inlet openings through opposite sides thereof below the upper end thereof, and air heating flues discharging heated air through said openings from opposite sides of the chamber.

In testimony whereof I affix my signature in presence of two witnesses.

WILLIAM A. EUDALY.
